By Wm. J. Belp
Attn

UNITED STATES PATENT OFFICE.

CHARLES M. WIBLE, OF MOUNT PLEASANT, PENNSYLVANIA.

DESIGN FOR A HEADLIGHT-LENS.

50,962.

Specification for Design.

Patented June 19, 1917.

Application filed March 17, 1917. Serial No. 155,623. Term of patent 3½ years.

To all whom it may concern:

Be it known that I, CHARLES M. WIBLE, a citizen of the United States, residing at Mount Pleasant, in the county of Westmoreland and State of Pennsylvania, have invented a new, original, and ornamental Design for a Headlight-Lens, of which the following is a specification, reference being had to the accompanying drawing, forming

a part thereof, in which the figure is a plan view of my headlight lens.

I claim:

The ornamental design for a headlight lens as shown.

CHARLES M. WIBLE.

Witnesses:

C. A. SHERRICK,
W. H. TEMPLETON.
